US0D1023504S

(12) **United States Design Patent** (10) **Patent No.:** **US D1,023,504 S**
(45) **Date of Patent:** **** Apr. 23, 2024**

(54) **CONFECTIONERY-COATED CONTAINER**(71) Applicant: **ZURU (SINGAPORE) PTE. LTD.**,
Central (SG)(72) Inventors: **Mathew Peter Mowbray**, Mid-levels
West (HK); **Chung Hyun Lee**, Seoul
(KR); **David Johnston Smith**,
Auckland (NZ); **Diwata Katrina**
Dinglasa Santillan, Auckland (NZ);
Ethan Luke Harrold, Auckland (NZ);
Ethan Hutchinson, Dairy Flat (NZ)(73) Assignee: **Zuru (Singapore) Pte. Ltd.**, Central
(SG)(**) Term: **15 Years**(21) Appl. No.: **29/913,228**(22) Filed: **Sep. 28, 2023****Related U.S. Application Data**(63) Continuation of application No. 29/889,447, filed on
Apr. 12, 2023, which is a continuation of application
No. 17/632,165, filed as application No.
PCT/SG2020/050461 on Aug. 7, 2020.(30) **Foreign Application Priority Data**Nov. 23, 2022 (AU) 202216915
Mar. 15, 2023 (AU) ..... 202311450(51) **LOC (14) Cl.** ..... **01-01**(52) **U.S. Cl.**USPC **D1/105**; D1/106; D1/127; D1/130
CPC **A23G 3/545** (2013.01); **B65D 11/02**
